FACE GUARD OR MASK

Peter J. Woloson, Elmira Heights, N. Y.

Application February 18, 1936, Serial No. 64,570

8 Claims.

(Cl. 2—9)

This invention relates to certain new and useful improvements in face guards or masks.

The primary object of the invention is to provide a face guard or mask especially designed for use in playing the game of soft ball and as contrasted with known masks used in the game of baseball and the like, the same is of a skeleton type to reduce the weight thereof to a minimum, being of one-piece construction whereby the same may be stamped or pressed to reduce the cost of manufacture and designed to give clear vision to the wearer thereof.

A further object of the invention is to provide a mask of the foregoing character wherein a leaf spring is positioned at the front side thereof to provide an effective shock absorber with flexure of the spring limited by a front bar of the mask frame, the mask frame carrying face engaging cushions or pads removably retained in position on the frame by spring devices.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a front elevational view of a soft ball mask constructed in accordance with the present invention;

Figure 2 is a side elevational view showing the shock absorbing spring at the forward side of the mask frame and the head strap carried by the temple bar;

Figure 3 is a detail sectional view taken on line 3—3 of Figure 2, showing the pad carried by the temple bar;

Figure 4 is a detail sectional view taken on line 4—4 of Figure 2, showing the pad carried by the chin bar; and

Figure 5 is a detail sectional view taken on line 5—5 of Figure 4.

Referring more in detail to the accompanying drawing, the face guard or mask that is especially designed for playing the game of soft ball comprises a skeleton frame including a forwardly arched vertical front bar 10 having a cross head of arcuate formation at its upper end constituting a temple bar 11. An arcuate foot extends transversely of the lower end of the front bar 10 and constitutes a chin bar 12. An arcuate arm projects laterally of each side of the front bar 10, being curved in the general direction of the temple and chin bars and constitutes cheek bars 13. The mask frame described is of one-piece

construction and may be stamped, molded or pressed and may be formed of any suitable light weight material, such as aluminum.

A shock absorbing spring 14 in the form of a strap or leaf is carried by the front bar 10 at the forward side thereof and as shown more clearly in Figure 2, recesses or pockets 15 are formed in the forward side of the front bar 10 for the reception of the ends of the leaf spring 14 with the spring spaced from the front bar as illustrated.

A temple pad is carried by the temple bar 11 and comprises a tubular casing 16 of soft leather or similar material with a padding insert 17 therein, the pad being connected to the temple bar 11 by means of a leaf spring 18 located interiorly of the casing 16 with the projecting ends 18a of the spring 18 at each end of the casing 16 having snap engagement with lugs 19 carried by the ends of the temple bar 11 at the inner side thereof.

A similar pad is carried by the chin bar 12 and is identified by reference characters corresponding to the temple pad, the projecting end 18a of the spring 18 having snap engagement with the lugs 20 carried by the opposite ends of the chin bar 12.

A head strap is carried by the mask and includes a crown strap 21 having a loop 22 at one end for sliding engagement with a band strap 23. The other end of the crown strap 21 is looped and provided with an adjustable clamp 24, the looped end of the strap carrying a tab 25 that is frictionally or otherwise retained in position between the temple bar 11 and temple pad. The opposite ends of the band strap 23 have pivoted link connections 26 with lugs 27 respectively projecting from the lower sides of each end of the temple bar 11.

When the mask is in position on the head of the user the arched front bar 10 and the cheek bars 13 are positioned forwardly of the nose and cheeks of the wearer while the pads 16 carried by the temple and chin bars 11 and 12 are engaged with the temple and chin of the wearer, the mask being retained in position by the head straps. It will be observed that the cheek bars 13 are so positioned as to permit clear vision of the wearer. The leaf spring 14 is arched forwardly of the front bar 10 and when contacted by a soft ball or other object during play of the game, the same flexes toward the front bar 10 and is limited in such movement by said bar, the spring 14 effectively absorbing shocks. In the event of wear or injury to the pads 16, the same

are easily removed from the mask frame by disengaging the ends 18a of the leaf springs from the lugs 19 and 20 of the temple and chin bars respectively. The face of the wearer is fully protected by the skeleton type of mask and advantages of this mask over prior known types are lightness in weight, inexpensive manufacture, resulting from the simplified construction and clear vision of the wearer in view of the placement and relationship of the several protecting bars.

While there is herein shown and described the preferred embodiment of the present invention, it is nevertheless to be understood that minor changes may be made therein without departing from the spirit and scope of the invention as claimed.

I claim:—

1. In a mask of the character described, a skeleton frame, including a vertical front bar, arcuate temple and chin bars extending transversely of the upper and lower ends respectively of the front bar, a head strap carried by the temple bar, and an arched leaf spring carried by the front bar and projecting forwardly thereof.

2. In a mask of the character described, a skeleton frame, including a vertical front bar, arcuate temple and chin bars extending transversely of the upper and lower ends respectively of the front bar, arcuate cheek bars extending laterally of the front bar, a head strap carried by the temple bar, a recess formed in the upper and lower ends of the forward side of the front bar, and a leaf spring having its ends removably received in the recesses and bulging forwardly of the front bar.

3. In a mask of the character described, a skeleton frame, including a vertical front bar, arcuate temple and chin bars extending transversely of the upper and lower ends respectively of the front bar, arcuate cheek bars extending laterally of the front bar, a head strap carried by the temple bar, and a pad carried by the temple and chin bars and including a leaf spring embedded therein and having projecting ends removably engaged with abutments of the associated bars.

4. In a mask of the character described, a skeleton frame, including a vertical front bar, arcuate temple and chin bars extending transversely of the upper and lower ends respectively of the front bar, a head strap carried by the temple bar, an arched leaf spring carried by the front bar and projecting forwardly thereof, and a pad carried by the temple and chin bars and including a leaf spring embedded therein and

having projecting ends removably engaged with abutments of the associated bars.

5. In a mask of the character described, a skeleton frame, including a vertical front bar, arcuate temple and chin bars extending transversely of the upper and lower ends respectively of the front bar, arcuate cheek bars extending laterally of the front bar, a head strap carried by the temple bar, a recess formed in the upper and lower ends of the forward side of the front bar, a leaf spring having its ends removably received in the recesses and bulging forwardly of the front bar, and a pad carried by the temple and chin bars and including a leaf spring embedded therein and having projecting ends removably engaged with abutments of the associated bars.

6. In a mask of the character described, a skeleton frame, including a vertical front bar, arcuate temple and chin bars extending transversely of the upper and lower ends respectively of the front bar, arcuate cheek bars extending laterally of the front bar, a head strap carried by the temple bar, the head strap including a crown strap and a band, one end of the crown strap being frictionally retained between the temple bar and pad and link and lug connections between opposite ends of the temple bar and band strap.

7. In a mask of the character described, a skeleton frame, including a vertical front bar, arcuate temple and chin bars extending transversely of the upper and lower ends respectively of the front bar, a head strap carried by the temple bar, an arched leaf spring carried by the front bar and projecting forwardly thereof, the head strap including a crown strap and a band, one end of the crown strap being frictionally retained between the temple bar and pad and link and lug connections between opposite ends of the temple bar and band strap.

8. In a mask of the character described, a skeleton frame, including a vertical front bar, arcuate temple and chin bars extending transversely of the upper and lower ends respectively of the front bar, arcuate cheek bars extending laterally of the front bar, a head strap carried by the temple bar, a recess formed in the upper and lower ends of the forward side of the front bar, a leaf spring having its ends removably received in the recesses and bulging forwardly of the front bar, the head strap including a crown strap and a band, one end of the crown strap being frictionally retained between the temple bar and pad and link and lug connections between opposite ends of the temple bar and band strap.

PETER J. WOLOSON.
